US00D946750S

(12) **United States Design Patent** (10) Patent No.: **US D946,750 S**
McLusky et al. (45) Date of Patent: **** Mar. 22, 2022**

(54) **GRIP ACCESSORY FOR AN INJECTION DEVICE**

(71) Applicant: **Janssen Pharmaceuticals, Inc.**, Titusville, NJ (US)

(72) Inventors: **James McLusky**, Edinburgh (GB); **Nick Foley**, Edinburgh (GB); **Jimmy Mower**, Edinburgh (GB); **Michael Cannamela**, Atlantic Highlands, NJ (US); **Peter Krulevitch**, Pleasanton, CA (US); **James Flint**, Hillsborough, NJ (US)

(73) Assignee: **Janssen Pharmaceuticals, Inc.**, Titusville, NJ (US)

(**) Term: **15 Years**

(21) Appl. No.: **29/676,220**

(22) Filed: **Jan. 9, 2019**

(30) **Foreign Application Priority Data**

(57) **CLAIM**

The ornamental design for a grip accessory for an injection device, as shown and described.

DESCRIPTION

FIG. 1 is a perspective view of a grip accessory for an injection device showing our new design;
FIG. 2 is a front elevation view of FIG. 1;
FIG. 3 is a side elevation view of FIG. 1;
FIG. 4 is a rear elevation view of FIG. 1;
FIG. 5 is a view of the opposite side of FIG. 3;
FIG. 6 is a top plan view of FIG. 1; and,
FIG. 7 is a bottom plan view of FIG. 1.

The portions shown in broken lines are unclaimed environment, and form no part of the claimed design.

1 Claim, 3 Drawing Sheets
